RAILWAY JOURNAL BOX OIL GUARD

James J. Hennessy, Chambersburg, Pa., assignor
to Hennessy Lubricator Company, Inc., Chambersburg, Pa., a corporation of Delaware

Application October 5, 1949, Serial No. 119,662

8 Claims. (Cl. 308—80)

1

The invention relates to the lubrication of railway axle journals of the type where the journal mounts a bearing and is enclosed in a box containing a quantity of oil which is fed to the journal to lubricate the surface supporting the bearing. To be effective, the lubricant must flow in at relatively low temperatures and be adapted to spread readily over the journal when the journal is moving at relatively low speeds. Hence, when the journal is rotating at relatively high speeds and is subject to relatively high temperatures, there is a tendency for the lubricant to flow along the journal and through the opening in the box wall through which the axle extends. This tendency is increased by the fact that the axle plays back and forth axially through the journal box wall and also has movement relative to the wall transversely of the journal axis. Various guards have been used in an effort to seal the space between the axle and the edge of the opening therefor in the journal box wall but such devices have been ineffective.

The main object of the present invention is to effectively seal the gap between the axle journal and the edge of the opening therefor in the journal box wall, irrespective of the speed of the journal, the amount of its axial or transverse play relative to the box, wear of the bearing and normal wear of the seal material conducting the journal, and other factors conducive to the loss of oil through the rear wall of the box.

The invention comprises a support structure and pad carrying parts mounted thereon for movement in various directions, relative to the support structure and preferably to each other also whereby their faces may be thrust against relatively movable axle and box parts.

Figure 1 is a longitudinal vertical central section through the lower portion of an outside bearing journal box, such as is commonly used on railway locomotive tender and trailer truck axles, equipped with an oil guard embodying the present invention, a portion of the associated axle and journal being shown in elevation.

Figure 2 is a front view of the oil guard in position in the journal box but without the journal in place and with one of the seal elements swung forwardly from its normal position for the purpose of better illustrating the structure.

Figure 3 is a top view of the structure shown in Figure 2.

Figure 4 is a detailed vertical section taken on the line 4—4 of Figure 2.

The box shown in the drawings has the usual

2

bottom wall 1, forward wall 2, side walls 3, and a rear wall 4 apertured at A for the passage therethrough of the axle 5 which terminates in the journal 6 and mounts a bearing (not shown) on which the box top wall (not shown) bears and supports the journal load. To accommodate variations in the diameter of the axle and the play of the axle in the box and variations in the thickness of the journal bearing there is a substantial gap G (Figure 1) between the axle and the edge of aperture A and it is the function of the present oil guard device to prevent the loss of oil through this gap.

The oil guard device is mounted upon a holding plate 7 having downturned flanges 8 which rest upon and may be welded to the box bottom wall 1. A mechanical pump actuated by the axial play of the journal in the box, as shown for example in Patent No. 2,178,891, issued to the present inventor November 7, 1939, may be positioned between legs 8 and to the left of the main body of plate 7 as indicated in Figure 1.

The oil guard device includes a support plate 9 mounted on holding plate 7 and positioned thereon by tongues 10 projecting through slots in plate 7. A torsion spring 11 has arms at its ends extending radially of its coil with one arm 11a anchored to base plate 9 and its other arm 11b extending upwardly and anchored to an upstanding spring plate 12 which extends substantially from side to side of the box. Spring plate 12 may swivel in a horizontal arc about spring arm 11b. Plate 12 may swing in a vertical arc about the axis of spring 11. Its movement in a clockwise direction (Figures 1 and 4) by thrust of spring 11 is limited by the engagement of lugs 12a with support plate 9.

An upright carrier plate 13 is slidable vertically along the right hand face of spring plate 12 and mounts vertical sleeves 14 near its ends. The major portion of each sleeve 14 is spaced from carrier plate 13 to form therewith a guide-way receiving spring plate 12. Stems 15 are slidable in sleeves 14 and are thrust downwardly by coil springs 16 so that the rounded lower ends of the stems engage base plate 9 and yieldingly thrust carrier plate 13 upwardly.

A pad 17 preferably of felt-like material is secured to the outer face of carrier plate 13 and the ends of the plate are flanged at 13a to more securely hold pad 17. The upper edge of pad 17 is cut arcuately corresponding to the lower portion of axle 5 which is engaged by pad 17.

A relatively small supplemental carrier plate 18 is pivoted to spring plate 12 by pintles 19 and

bearings 20 to swing in a vertical arc similarly to the previously mentioned swinging of plate 12 and is yieldingly thrust in a clockwise direction (Figures 1 and 4) by torsion springs 21, each having its arms bearing against plates 12 and 18 respectively. The upper portion of supplemental plate 18 is inclined relative to its lower mounted portion and a pad 22 preferably of felt-like material is secured to the left hand face of this inclined upper portion. The top edge of pad 22 is cut arcuately to correspond to the peripheral curvature of the fillet F between journal 6 and the adjacent portion of the axle.

When the guard is positioned as shown in Figure 1 and the journal box and axle are assembled, pad 17 is thrust rearwardly by spring 11 so that the pad contacts the inner face of the journal rear wall 4. At the same time, the pad is thrust upwardly by springs 16 so that the upper edge of the pad contacts the periphery of axle 5 just inside of box wall 4. Pad 22 is thrust rearwardly and upwardly by springs 21 so that its upper edge is thrust against fillet F. Pads 17 and 22 are mounted to move independently of and relative to each other in various directions so that they may be thrust tightly against the journal axle and the box rear wall, irrespective of variations in the sizes of the journal and axle, or in the spacing of fillet F from the box rear wall due to variations in dimensions of the axle, journal and box and variations in the play of the axle lengthwise of the box. In other words, pad 22 can follow the journal in its movements vertically, transversely or longitudinally of the box without affecting the contact of pad 17 with the axle and the rear wall of the box and the edge of pad 22 is not broken or worn down unduly because of the above-mentioned movement of the journal as would be the case if pad 22 were fixed in respect to pad 17.

The oil guard is readily applied and removed from the journal box as a unit and the individual pads of the oil guard may be assembled and disassembled for replacement or repair. The smaller pad 22 acts as a wiper to remove surplus oil flowing to the right along the lower portion of the journal and the larger pad 17 and seals the gap between the axle and the edge of the axle opening in the journal box rear wall and prevents the flow of any oil to the right which is not caught by pad 22.

The pads may consist of wood or other fibers rather than felt and the details of the mounting of the pads may be varied substantially from those shown without departing from the spirit of the invention and the exclusive use of those modifications coming within the scope of the claims is contemplated.

What is claimed is:

1. In an oil guard for a railway axle journal box, a horizontally disposed support plate, an upstanding plate, hinged structure mounting said upstanding plate on said support plate, a supplemental upstanding plate hinged on said upstanding plate, said structure including spring means thrusting said upstanding plates upwardly and rearwardly of said support plate, and individual pads of fibrous material mounted on said upstanding plates with their upper edges shaped to fit the contour of a railway journal and adjacent axle portion.

2. In an oil guard for a railway axle journal box, a horizontally disposed support plate, a plate extending upwardly therefrom, a torsion spring having a radial arm at one end anchored

to the support plate and a radial arm at its other end secured to the upstanding plate, said spring providing a hinge assembly for the two plates, a carrier slidable vertically along one side of said upstanding plate, a fibrous pad on said carrier arranged for contact with a portion of an axle to which the guard is applied, a supplemental carrier hinged to the opposite side of said upstanding plate, and a pad of fibrous material mounted on said supplemental carrier, there being yielding means thrusting both of said carriers and the associated pads away from said support plate.

3. An oil guard as described in claim 1, in which the mounting for the first-mentioned upstanding plate includes means providing for the swiveling of said upstanding plate on said support plate about an upright axis.

4. In combination with a railway axle journal box having a bottom wall and a rear wall, an associated axle and journal, a holding plate adjacent the bottom of the box and having slots near the rear end of the box, an oil guard device including a support with depending tongues inserted in said slots to position the device on the holding plate when the support is at rest while accommodating their ready disassembly when the support is tilted, an upstanding pad of fibrous material having a mounting on said support which accommodates the movement of said pad into contact with the inner face of the rear wall of the box and the movement of the upper edge of said pad into contact with an axle upon which the box is mounted, an upstanding pad of fibrous material spaced from said first-mentioned pad and having a mounting associated with said first-mentioned mounting which accommodates movement of the associated pad upwardly and longitudinally of the box relative to the first-mentioned pad.

5. Structure as described in claim 1 in which the mounting for the first-mentioned pad may swivel on the holding plate at an angle to its hinge movement and the mounting for the second-mentioned pad is carried on the mounting for the first-mentioned pad.

6. In an oil guard for a railway axle journal box, a pad with an arcuate upper face disposed to engage a journal to which the guard is applied, and a pad with a similarly arcuate upper face having a different radius, a common support, a device for pivotally mounting one of said pads on said support, and structure independently pivotally mounting the other of said pads on said device, there being individual means yieldingly thrusting said pads about their pivotal mountings and upwardly away from said common support, and stops limiting the action of said means.

7. In an oil guard for a railway axle journal box, a support member, a pair of wide, relatively thin pads of fibrous material with their upper edges comprising concave arcs of different radii, a device mounting one of said pads on said support and yieldingly thrusting the same edgewise and away from said support, means pivotally mounting the other of said pads on said device and yieldingly thrusting the same edgewise away from said support and angularly towards the other pad.

8. In combination with a railway axle journal box, having a bottom wall and a rear wall, and an associated axle including a main portion and a journal of smaller diameter, there being a fillet between said journal and portion, a pair of

relatively wide, thin pads of fibrous material extending transversely of the axle axis and having arcuate upper edges with different radii corresponding to the radii of said fillet and portion, respectively, structure mounted on the box bottom wall and yieldingly thrusting the pad with the larger radii upwardly against said portion, and a device pivoted on said structure and yieldingly thrusting the pad with the smaller radii angularly upwardly against said fillet.
